[57] **CLAIM**

The ornamental design for a belt elevator type educational toy, as shown and described.

DESCRIPTION

FIG. 1 is a perspective view of a belt elevator type educational toy showing my new design;

FIG. 2 is an end elevation view thereof;

FIG. 3 is a top plan view thereof;

FIG. 4 is a front elevation view thereof;

FIG. 5 is a side elevation view thereof from the right side of FIG. 3; and

FIG. 6 is a bottom plan view thereof.

The illustrations of the "letter blocks" in FIG. 2 and FIG. 5 are sketchily depicted for ease of illustration.
